UNITED STATES PATENT OFFICE

CLEMENS ROHLFES, OF SAN FRANCISCO, CALIFORNIA

PRICE MARKING DEVICE

Application filed September 29, 1930. Serial No. 425,121.

My invention relates to improvements in price marking devices wherein a mounting member is provided with a plurality of strips each having price marking characters thereon and foldable to expose a desired character upon each strip for observation through an opening in the front of the mounting member.

The primary object of my invention is to provide an improved price marking device. Another object is to provide an improved price marking device wherein each of a plurality of strips bearing appropriate price marking characters are independently foldable to expose a desired character, the several strips being disposed in parallel relation to expose their characters in desired relation.

A further object is to provide an improved device of the character described wherein strips having characters on both sides thereof may be folded to expose a desired character on either side in upright position.

Another object is to provide an improved price marking device affording a wide range of adjustment and which will facilitate the adjustment to display a desired price.

A further object is to provide an improved device of the character described of extremely simple, compact and economical construction, which is simple and efficient in operation, and which is attractive in appearance.

A still further object is to provide an improved article embodying improved details of construction and arrangement.

I accomplish these and other objects by means of the improved device disclosed in the drawings forming a part of the present application wherein like characters of reference are used to designate similar parts throughout the specification and drawings, and in which:—

Fig. 1 is a front elevation of my improved price marking device, parts being broken away;

Fig. 2 is a perspective view of the device,

showing the manner in which the strips are arranged to be folded;

Fig. 3 is a transverse section of the device; and

Figs. 4, 5, and 6 are diagrammatic views 50 showing various ways in which each strip may be folded to expose various characters.

Referring to the drawings, the numeral 1 is used to designate in general a mounting member having an opening 2 in the front 55 thereof and provided with a plurality of foldable strips 3 having price marking characters 4 thereon.

The mounting member 1 is formed from card-board, or other suitable material, and 60 preferably consists of a back member, an intermediate member, and a front member secured in proximate relation, and designated in Fig. 3 by the reference characters 1^a, 1^b, and 1^c, respectively. The intermediate member has an opening 2^a, preferably rectangular in form, covered across the back by the back member 1^a. The opening 2 of the front member 1^c substantially matches with the opening 2^a, but the edges of the front member 1^c are 70 extended to overhang the opening 2^a upon opposite sides of the opening, as at 5, thereby forming recesses between the front and back members along the edges of the opening 2. The mounting member 1 may of course be 75 made of any desired size or shape, and the front may be decorated in any desired manner to present an attractive appearance or form of advertising display.

The strips 3 are formed from paper or 80 other suitable material and are attached at one end upon the mounting member by any convenient securing means. The strips 3 are folded upon transverse lines of fold 6 into a plurality of panels of equal length, 85 each panel having a character upon the front and back thereof. The panel nearest the attached end of each strip is provided with a transverse fold 7 approximately midway of its length, and no character 4 is provided 90

upon this panel. The characters upon the front side of the strips 3 are arranged in normal upright position with the top of each character disposed toward the attached end 5 of its strip. The characters upon the back of the strips 3 are disposed in the opposite direction so that the top of each character will be disposed toward the free end of its strip, the characters upon opposite sides of each 10 panel thereby being disposed in opposite relation. The characters 4 upon certain of the strips consist of numerals arranged successively from the attached end upon the front of said strips, and upon the backs of 15 the strips from the free end toward the attached end as shown upon the extended strip 3 of Fig. 2. Characters representing units of measure or other designation are arranged upon the remaining strip or strips 3.

20 In operation, the strips 3 are folded upon the lines of fold 6 so that the several panels of each strip are disposed in matching proximate relation, and the ends of the folded strips are inserted into the recesses formed 25 by the overhanging edges 5 of the front member 1^a whereby the folded strips are held flat within the recess formed by the opening 2^a. In folding the strips, the several panels are foldable in either direction upon the lines 30 of fold 6 whereby the panels may be folded in zig-zag fashion to expose a desired character. When a strip has been folded in desired manner, the ends of the folded strip are inserted under the overhanging edges 5 of the 35 front member.

As certain figures will be inverted relative to others and to the mounting member, the folded strip must be inserted in a position such that the character will be disposed in 40 upright position relative to the mounting member. This is accomplished by means of the blank panel and its intermediate fold 7. Thus, when the desired character is normally disposed in upright position when the strip 45 is folded to expose that character, the blank panel is folded and doubled back upon itself upon the fold 7, as indicated in Figs. 3 and 4 of the drawings, thereby permitting the ends of the folded strip to be inserted under the 50 edges 5 in the relation shown in Fig. 3. When the position of the character is reversed, the blank panel is extended to its full length and the remaining portion of the strip is folded upwardly to match with the blank panel as 55 indicated in Figs. 5 and 6. The manner of folding each strip of course varies according to the panel and character to be exposed. Thus, the strip may be folded in straight zig-zag manner as shown in Figs. 4 and 5, or one 60 or more of the panels may be interfolded between other panels, as indicated in Fig. 6. As the strip is readily foldable in either direction along the lines of fold 6, any panel may be selected at will and the remaining 65 panels are folded in back of the selected panel

in the most convenient manner, and the blank panel extended or doubled to dispose the displayed character in upright manner.

The several strips are disposed side by side within the opening of the mounting members 70 so that the several characters are readable together to designate a price. The folded strips are normally retained in operative displayed position, as indicated in Figs. 1 and 3. When a strip is to be adjusted to display a different character, the desired strip is withdrawn from engagement by the overhanging edges 5 and extended, as indicated in Fig. 2. Openings 8 are formed in the back member 1^a whereby the folded strips may be engaged and displaced from the backing members as desired, an opening 8 preferably being formed in back of each strip so that any one strip may be displaced without disturbing the other strips.

80 While I have illustrated and described what I regard as the preferred embodiment of my invention, the device may of course be modified in various details of construction and arrangement without departing from the spirit of my invention. I therefore desire to avail myself of all modifications which may fall within the scope of the appended claims.

Having thus described my invention, what 85 I claim as new and desire to secure by Letters Patent is:

1. A price marking device comprising a mounting member having an opening in the front thereof; a plurality of strips each attached at one end to the mounting member and having transverse folds at regularly spaced points to form a plurality of panels having price marking characters thereon, the panels being foldable in either direction upon the transverse folds into superimposed matching relation, with a desired character exposed upon the outermost panel, and the folded strips being insertable into operative positions within the opening; and means to engage the ends of the folded panels to retain the same within the opening.

2. A price marking device comprising a mounting member having an opening in the front thereof; a plurality of strips each attached at one end to the mounting member and having transverse folds at regularly spaced points to form a plurality of panels having price marking characters thereon, the panels being foldable in either direction upon the transverse folds into superimposed matching relation, with a desired character exposed upon the outermost panel, and the folded strips being insertable into operative positions within the opening; and flanges upon the mounting member to form recesses at opposite edges of the opening to engage the ends of the folded panels to normally retain the same within the opening.

3. A price marking device comprising a

- mounting member having an opening in the front thereof and having recesses along opposite sides of the opening; a plurality of strips each attached at one end to the mounting member and having transverse folds at regular intervals to form a plurality of panels of equal length, the panel nearest the attached end of the strip having a transverse fold midway of the length thereof, and the other panels having price designating characters thereon, the panels being foldable in either direction upon the transverse folds in zig-zag manner to present a panel having a desired character in exposed position, and the innermost panel being foldable upon its transverse fold to invert the position of the character bearing panels relative to the backing member, the ends of the folded panels being insertable into the recesses at opposite sides of the opening to normally retain the panels in operative position within the opening. 5
4. A price marking device comprising a mounting member having an opening in the front thereof and having recesses along opposite sides of the opening; a plurality of strips each attached at one end to the mounting member and having transverse folds at regular intervals to form a plurality of panels of equal length, the panel nearest the attached end of the strip having a transverse fold midway of the length thereof, and the other panels having price designating characters thereon, the panels being foldable in either direction upon the transverse folds in zig-zag manner to present a panel having a desired character in exposed position, and the innermost panel being foldable upon its transverse fold to invert the position of the character bearing panels relative to the backing member, the ends of the folded panels being insertable into the recesses at opposite sides of the opening to normally retain the panels in operative position within the opening; and openings in the back of the mounting members whereby the folded panel strips may be engaged and pressed outwardly from engagement with the recesses. 10
5. A price marking device comprising a mounting member having a recess in the front thereof; a front piece mounted upon the front of the mounting member and having edges overhanging the recess of said mounting member; a plurality of strips having price designating characters thereon and each foldable upon transverse lines of fold to expose a desired character, the strips being attached at one end upon the backing member in proximate parallel relation, and the ends of the folded strips being insertable under the overhanging edges of the front member to normally retain the strips in operative price displaying positions within the recess. 15
6. A price marking device comprising a mounting member having a recess in the front thereof; a front piece mounted upon
- the front of the mounting member and having edges overhanging the recess of said mounting member; a plurality of strips having price designating characters thereon and each foldable upon transverse lines of fold to expose a desired character, the strips being attached at one end upon the backing member in proximate parallel relation, and the ends of the folded strips being insertable under the overhanging edges of the front member to normally retain the strips in operative price displaying positions within the recess; and openings formed in the back of the mounting members in back of each folded strip. 20
7. A price marking device comprising a mounting consisting of a back member; an intermediate member attached to the back member and having an opening spaced from the edges thereof and covered across the back by the back member; a front member attached across the front of the intermediate member and having an opening substantially matching with the opening in the intermediate member, edges of the front member overhanging the opening in the intermediate member to form recesses between the front and back members at opposite sides of the openings; and a plurality of strips attached at one end to the mounting and having a plurality of price designating characters thereon, the strips being foldable to expose desired characters and the ends of the folded strips being insertable into the recesses at the edge of the opening to normally retain the strips in operative price displaying position with the desired character of each strip exposed through the opening in the front member. 25
8. In a price marking device, the combination with a backing member having an opening in the front thereof, of a plurality of strips attached at one end upon the backing member and foldable for insertion into displaying positions within the opening, each strip having price marking characters spaced longitudinally therealong upon each side of the strip, said strips being foldable upon transverse lines of folds defining panels of equal length, each bearing a character on both sides thereof, and the panel nearest the attached end of each strip being foldable upon a transverse fold midway between its ends whereby the folded strips may be inserted to display a desired character carried on either side of the strip in upright position. 30
9. In a price marking device, the combination with a backing member having an opening in the front thereof, of a plurality of strips attached at one end upon the backing member and foldable for insertion into displaying positions within the opening, each strip having price marking characters spaced longitudinally therealong upon each side of the strip, said strips being foldable upon

transverse lines of folds defining panels of equal length, each bearing a character on both sides thereof, and the panel nearest the attached end of each strip being foldable upon a transverse fold midway between its ends whereby the folded strips may be inserted to display a desired character carried on either side of the strip in upright position; and means upon the backing member to receive and engage the ends of the folded strips.

In witness whereof, I hereunto set my signature.

CLEMENS ROHLFES.
